BOWDEN WASHINGTON, OF NEW YORK, AND WILSON AULL, JR., OF ASTORIA, NEW YORK, ASSIGNEES TO REMOTROLE CORPORATION, A CORPORATION OF NEW YORK

REMOTE CONTROL FOR RADIORECEIVERS

Application filed June 13, 1927. Serial No. 198,470.

One object of our invention is to provide a simple and easy manner of turning on and off the filaments of a radio receiver from the loud speaker no matter where the latter may be located, and without causing a drop of filament voltage at the vacuum tubes which would be the case if the filament current was caused to flow through long extension wires of small cross section.

10 Another object is to be able to control from a point near the loud speaker the volume of the sound produced without spoiling the quality.

It is becoming more and more usual to use 15 extension cords sometimes of considerable length in which case the listener has to go to the receiver to turn off the filaments. A particular instance of this may be given to show its usefulness in the broadcasting of "morning exercises". In this case the radio receiver would normally be placed in the living 20 room, while the user might desire to take exercises in his own room or on a porch immediately upon arising. By means of our invention he could before retiring tune to the 25 station which normally transmits the material for the morning exercises and bring the loud speaker to the exercising place. Upon arising at the predetermined hour he would 30 light the filaments of his receiver from or at the loud speaker, thus putting the set into operation and upon finishing the exercises turn off the filaments without the necessity of going downstairs or into another room where 35 the receiver is located.

The drawing shows one form of our invention applied to a radio receiver having direct audio frequency out-put.

Referring to the drawing the plate 5 of the 40 last audio frequency amplifier tube 6 of the set is connected in the usual manner to one wire of the extension cord 7 terminating in a plug socket or jack 8. The speaker 9 by its cord 10 is connected to the usual plug 11. The positive terminal of the B power supply such as battery 12 is connected in the usual manner to one conductor of the cord 7.

The relay 13 is of low resistance and may 50 be of the delay type in order to have a time response factor suited to the desired se-

quence of action including the heating of the filaments. It is connected in series with the A battery 14 and the filaments. It is normally held in the closed position by the spring 15. The relay 16 is of comparatively higher 55 resistance and may be operated by the direct current component of the loud speaker input. It is normally held open by the spring 17. The resistance 18 is preferably of the general order of value of the plate filament 60 impedance of the tube 6. In order to control the volume preferably without affecting the plate voltage we may provide a transformer 19 in the loud speaker circuit with a voltage 65 divider or potentiometer 20 across the secondary so arranged that any desired fractional part of the voltage may be delivered to the loud speaker 9 or the current to the speaker may be turned off.

In operation when the plug 11 is inserted 70 into the jack 8 current from the B battery 12 goes through the loud speaker and back through the resistance 18, through the contacts of the relay 13 and through the windings of the relay 16 back to the battery, thus energizing the magnet of the relay 16 and closing its contacts. When this closure is effected, the filaments are heated but it will be seen that in series with these filaments is the low resistance relay 13 which becomes 75 energized and disconnects one end of the resistance 18 from the circuit after the filaments are sufficiently heated to allow the passage anode current.

When the plug 11 is pulled out of the jack 85 8 the plate current, which has held closed the relay 16, is broken, thus breaking the filament circuit and at the same time allowing the relay 13 to close.

The resistance 18 serves as a path for the 90 plate or B current when the tube 6 is cold and is cut out after the filament circuit is closed by the relay 16.

The plug and jack serve as a switch to interrupt and/or close the loud speaker circuit.

Suitable by-pass condensers (not shown) may be employed in parallel with any or all of the relays or resistances used in order to reduce signal loss therein, as well known in the art.

Household wiring and piping systems may be utilized in whole or in part for the extension conductors 7. The transformer, potentiometer and plug switch may be sold and mounted as a single unit either for insertion 5 between the receiver and the speaker or to be connected by an extension cord to the speaker base.

It should be understood that other modifications 10 may be made within the broad scope of our invention. Obviously the details of the radio receiver and the type of loud speaker are immaterial.

We claim:

15. 1. In a vacuum tube radio receiver having a loud speaker, the combination of a switch in the loud speaker circuit, a relay having a coil in the plate circuit and having a switch member in the filament circuit, the current 20 in the plate circuit being normally sufficient to hold the filament circuit closed, a relay having a coil in the filament circuit and a switch in an auxiliary plate circuit and a substantially constant impedance volume 25 control deriving its energy input from the conductors supplying the first mentioned switch in the loud speaker circuit.
2. A vacuum tube radio receiver having an A battery, a B battery and a loud speaker, a relay connected to the A battery, a switch and volume control of substantially 30 constant impedance located at the loud speaker, said switch, volume control and loud speaker being connected to the radio receiver by 35 a single pair of conductors and circuit connections for closing the B battery circuit and automatically operating the relay and lighting the filaments when said switch is closed including a switch and an operating coil in 40 the filament circuit.
3. A radio receiver combination adapted for distant control including a radio receiver having electronic tubes, a source of cathode heating potential and a source of anode potential 45 furnishing energy thereto, a shunt circuit from the cathode source to the anode source, a lighting relay with its operating coil in the anode circuit and its contacts closing the filament circuit, and a cut-off relay 50 with its operating coil in the filament circuit and its contacts opening said shunt circuit so that normal space current flow is established upon its operation.
